MARINE VESSEL

John Brunt, Kenilworth, N. J.

Application August 3, 1942, Serial No. 453,405

2 Claims. (Cl. 114—66.5)

This invention appertains to new and useful improvements in marine vessels, the principal object of the present invention being to provide a vessel of the character stated built for extremely high speed.

Another important object of the invention is to provide a marine vessel constructed in such a manner as to rise most of the way out of the water when traveling at a fast rate of speed, thus materially reducing the chance of being struck by torpedoes during wartimes.

Still another important object of the invention is to provide a marine vessel which can be employed as a cargo ship with a view toward transporting oils, foods and even troops during wartime at a much higher rate of speed.

Other objects and advantages of the invention will become apparent to the reader of the following description.

In the drawings:

Figure 1 is a top plan view of the vessel.

Figure 2 is a side elevation.

Figure 3 is a front elevation.

Figure 4 is a longitudinal vertical section.

Figure 5 is an enlarged fragmentary horizontal sectional view taken substantially on the line 5—5 of Figure 2.

Figure 6 is a vertical transverse sectional view taken substantially on the line 6—6 of Figure 2.

Figure 7 is a fragmentary detailed vertical section taken substantially on the line 7—7 of Figure 3.

Referring to the drawings wherein like numerals designate like parts, it can be seen in Figure 6, that numeral 5 denotes a top deck while numeral 6 denotes a bottom deck and extending longitudinally of the bottom deck 6 and in parallel spaced relation beneath the same are elongated air chambers or pontoons 7, 7. The decks 5, 6 and the pontoons 7 may have common ship sides 8, 9 and in the upper portions of the sides 8, 9 above the deck 6 are port holes 9. Longitudinally extending partitions 10 are provided between the decks 5, 6 and these may have suitable doorways or other openings 11.

As can be seen in Figure 4, the deck 6 terminates at the forward point 12 where a sloping shed 13 starts to rise and terminates at a point above the bow ends of the pontoons 7, 7. From the upper portion of the shed 13 and rearwardly on the deck 5 is a cabin structure 14, having suit-

able doors 15 and port holes or windows 16. A windshield 17 is provided in its slanting forward wall 18.

Suitable brackets 19 are secured to the water 5 opposed side of the shed member 13 for the purpose of supporting one or more motors 20 each having a propeller 21.

These propellers serve to pull air into the tunnel 22 formed by the shed 13, deck 6 and pontoons 10 7, 7, this tunnel being open at its forward end and also at its rearward end where a rudder 23 is provided and controlled by suitable control means 24 at the stern end of the deck 6.

It can now be seen, that when the engines 29 15 are started, the propellers 21 will pull and push air into the tunnel 22. This air will build up between the shed 13 and the water and eventually within the confines of the pontoons 7, 7 with a result that as the 20 vessel develops momentum, it gradually rises from the water and is eventually actually riding on an air current.

While the foregoing specification sets forth the 25 invention in specific terms, it is to be understood that numerous changes in the shape, size and materials may be resorted to without departing from the spirit and scope of the invention as claimed hereinafter.

Having described the invention, what is claimed 30 as new is:

1. A marine vessel comprising a deck structure including upper and lower decks, respectively, and a pair of elongated side pontoon structures disposed in spaced parallel relation under the deck structure, the forward portion of the lower deck rising obliquely above the upper deck, and a cabin on the upper deck extending aft from the obliquely rising forward portion, the front of the cabin being formed in part by said portion.

2. A marine vessel comprising a deck structure including upper and lower decks, respectively, a pair of elongated side pontoon structures disposed in spaced parallel relation under the deck structure, the forward portion of the lower deck rising obliquely above the upper deck, and a cabin on the upper deck extending aft from the obliquely rising forward portion, the front of the cabin being formed in part by said portion, and motor operative propellers mounted on said portion above the water line.
